(57) **CLAIM**

I claim the ornamental design for a lockable under-deck storage unit, as shown and described.

DESCRIPTION

FIG. 1 is an isometric view of a lockable under-deck storage unit showing my new design;

FIG. 2 is a front elevational view thereof;

FIG. 3 is a rear elevational view thereof;

FIG. 4 is a top plan view thereof;

FIG. 5 is a right side elevational view thereof, the left side elevational view being a mirror image thereof; and,
FIG. 6 is an isometric view showing the lockable under-deck storage unit in use; the broken lines show environment structure for illustrative purposes only and form no part of the claimed design.
